UNITED STATES PATENT OFFICE

168,965

FLASHLIGHT OR SIMILAR ARTICLE

William Kendall Overturf, San Diego, Calif.

Application October 11, 1952, Serial No. 21,812

Term of patent 14 years

(Cl. D48—24)

To all whom it may concern:

Be it known that I, William Kendall Overturf, a citizen of the United States, residing at San Diego, in the county of San Diego and State of California, have invented a new, original, and ornamental Design for a Flashlight or Similar Article, of which the following is a specification, reference being had to the accompanying drawing, forming part thereof.

In the drawing:

I claim:

The ornamental design for a flashlight or similar article, substantially as shown.

WILLIAM KENDALL OVERTURF.
